UNITED STATES PATENT OFFICE.

WILLIAM R. McKEEN, JR., AND BARTHOLOMEW JULIEN, OF OMAHA, NEBRASKA.

CAR-HEATER.

1,146,187.

Specification of Letters Patent. Patented July 13, 1915.

Application filed June 16, 1909. Serial No. 502,410.

To all whom it may concern:

Be it known that we, WILLIAM R. McKEEN, Jr., and BARTHOLOMEW JULIEN, citizens of the United States, residing at Omaha, in the county of Douglas and State of Nebraska, have invented certain new and useful Improvements in Car-Heaters, of which the following is a full, clear, and exact description, such as will enable others skilled in the art to which it appertains to make and use the same.

This invention relates to car heaters and the like.

One of the objects thereof is to provide a simple and practical heater adapted for convenient use in emergencies as in the case of a train becoming snow-bound or otherwise stalled.

Another object is to provide a car heater of this general nature which can be conveniently stored on a passenger car and which may be quickly and securely assembled to perform its functions when necessary.

Another object is to provide a heater of this type which is compact and durable and which will prove efficient and practicable in service.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, in which is shown one of various possible embodiments of the invention, Figure 1 is a side elevation of the heater in its assembled position within a car, the positions of the parts when stored being indicated in dotted lines; Fig. 2 is an end view of one of the seats of a car, showing a portion of the heater stored beneath it; Fig. 3 is a side elevation of the base of the heater, the ash pit door being removed; Fig. 4 is a plan view of Fig. 3, parts being broken away for the sake of clearness; Fig. 5 is a side elevation of the body of the heater, the fire box door being removed; parts being shown in section. Fig. 6 is an elevation of the smoke pipe, parts being shown in section; Fig. 7 is a sectional view taken on a line $x-x$ of Fig. 5; Fig. 8 is a vertical sectional view through

a floor plate and a portion of the base of the heater showing the mode of attachment of the heater to the floor. Fig. 9 is a front elevation of one of the heater doors, parts being broken away for the sake of clearness; Fig. 10 is a sectional view taken on the line $y-y$ of Fig. 9.

In order to render more readily and fully understood certain objects of this invention, it may here be noted that in the use of the ordinary system of steam heating as applied to railroad trains, if a car is cut off from the train, means independent of the locomotive must be employed for heating the car, if it is desired to maintain it at a normal temperature. Also it may happen that in severe weather there may not be sufficient steam to heat the car comfortably, in which instance other means should be at hand to accomplish this object. In either of the above or other emergencies, it is desirable to have efficient heating means without an undue occupation of space.

The above and other objects are attained by means of apparatus of the nature herein-after described.

Referring now to the drawings, 1 indicates the base portion of the heater comprising an ash-pit 2 having a bottom 3 below which the walls of the base extend a suitable distance in order to provide a space between the bottom of the ash-pit and the floor of the car. Openings 4 are formed in the portion of the wall which extends below the ash-pit bottom in order to provide a circulation of air beneath the same for preventing over-heating of the floor. One or more openings 5 are provided to receive the fastening means by which the heater is secured to the floor as hereinafter described.

An opening 6 is provided which is adapted to be closed by a door as hereinafter described, and through which the ashes may be removed in the usual manner. A grate 7 is positioned in the upper portion of the base 1 which may be of any suitable construction, that shown being provided with trunnions 8 placed eccentrically with respect to the diameter of the grate and supported in bearings 9 formed in the base. One of the trunnions is provided with a squared extension 10 adapted to receive a shaker in the usual manner. In order to hold the grate normally in a horizontal position, a lug 11 is provided with the upper surface of which the grate is adapted to engage, as shown in

Fig. 3. Adjacent its upper end the base is provided with a shoulder 12 with which the lower end of the body portion 13 of the heater is adapted to engage. Upon base 1 5 are lugs 14 adapted to engage slots 15 formed in the body portion, thus providing a joint of the bayonet type. The body portion 13 is cut away as at 16 to form a fuel opening closed by a door, as hereafter described. Handles 17 are preferably secured to the body portion in order to enable the same to be easily handled and carried about. At its upper end the body portion is provided with a smoke opening 18, preferably 10 surrounded by a flange 19 which may be secured thereto in any suitable manner as for example by rivets, as shown in Fig. 5. A damper 20 registers with the smoke opening 18 and is mounted upon a damper-rod 20 21, the ends of which extend through the flange 19, and a collar 22, also mounted upon the damper-rod, surrounds the flange and is spaced therefrom for a purpose herein-after described. In assembling these parts, 25 the body portion 13 is so positioned as to permit the lugs 14 upon the base portion 1 to enter the vertical portion of the slots 15, after which the body portion is turned slightly to cause the lugs to engage the inner 30 ends of the horizontal portions of the slots, thereby securely locking the parts in position.

An adjustable smoke pipe 23 is formed of a plurality of sections adapted to telescope 35 within one another, as indicated in Fig. 6, and the lower end of the pipe is provided with a slot 24 adapted to engage and interlock with the damper-rod 21 when this end of the pipe is inserted between the flange 19 40 and the collar 22. Adjacent its other end the pipe is provided with a flange 25 preferably in the form of a ring, which may be riveted or otherwise secured to the pipe, and which, when the pipe is placed in position, 45 registers with a perforated plate 26 secured at a suitable place within the car, as for example upon its ceiling, from which it is preferably spaced by spacing members 27 in order to prevent the ceiling from becoming 50 over-heated. The upper end of the smoke pipe projects through the perforation in the plate and through a suitable opening in the ceiling of the car which opening is protected by a hood 28 of any usual construction as is common in devices of this 55 character.

The telescopic construction of the smoke pipe enables it to be accurately adapted in length to the height of the vehicle, or the 60 distance between the top of the stove and the smoke pipe opening, and further permits the pipe to be contracted or shortened, and placed within the stove body when the stove is dismantled for storing.

65 Referring now to Figs. 9 and 10, in which

one of the heater doors is shown, 29 indicates the door, which is hinged to a door-frame 30, riveted or otherwise secured to the heater. As both the fire-pot and ash-pit doors are of the same construction, one only 70 will be described.

The door, which is preferably provided with a liner 31 of any suitable construction, has draft openings 32 formed therein in the usual manner. In order to regulate 75 the amount of air which passes through the draft openings, a draft-plate 33 is provided which is mounted upon a pin 34, the inner end of which is threaded and engages a threaded perforation in the door. To the 80 outer end of the pin 34, which extends through the draft-plate, a handle 35 may be secured in any desired manner. From the above description it will be understood that by rotating the handle the draft-plate 85 may be caused to move away or toward the door, depending on the direction of rotation of the handle, thus forming a practical and accurate means of regulating the amount of air which flows through the draft 90 openings 32 in the door. A latch is provided whereby the door may be maintained in its closed position, the handle 36 of which is preferably of the same size and shape as the handle of the draft-plate whereby they are 95 interchangeable.

For enabling the heater to be rigidly secured to the floor of the car when in use, one or more floor plates 37 are provided, each of which comprises an apertured upper portion 100 38 and a downwardly extending portion 39, provided with a threaded opening 40 registering with the aperture in the upper portion, the downwardly extending portion being preferably inclined as clearly shown 105 in Fig. 8. The floor plates are preferably positioned between adjacent car-seats and secured to the floor by means of screws taking through opening 40, and are preferably so arranged that the upper surfaces are 110 flush with the car flooring.

The operation and use of the device is as follows: When it is desired to use the heater, the base portion 1 is placed in position upon the floor of the car with the openings 5 115 formed therein registering with the aperture formed in the floor plates 37 and suitable fastening means such as set-screws 42 are inserted in the registering openings and engage the threaded portion 40 of the floor plates thereby securely holding the base in position. The body portion is then placed in position with its slots 15 engaging the lugs 14, on the base portion, as above described. The smoke pipe 23 is then secured to the body portion 13, as above described, with which it is interlocked through the agency of the slots 24, which, as above described, engage with the damper-rod. The 120 upper portion of the smoke pipe is then car- 130

ried upward to pass through the openings in the plate 26 and car roof with the flange 25 engaging the plate 26 to which it is secured in any suitable manner as by means of one or more set-screws 43 passing through and engaging threaded openings in the flange and plate, as indicated in Fig. 1. The heater is now in its assembled position and may be operated in the usual manner. When it is desired to remove the same, it is merely necessary to reverse the operations above described, after which the parts may be stored away ready for future use.

For storing the various parts, there are provided a plurality of receptacles 44, preferably of metal, located beneath the car seats and supported upon the car flooring, within which the parts are adapted to be placed, as indicated in dotted lines in Fig. 1. There are preferably two of these receptacles one of which is adapted to hold the base portion 1 and the other of which is adapted to hold the body portion 13 within which the stove-pipe 23 may be inserted in its telescoped condition. Suitable covers 45 may be provided for the receptacles, having handles 46 secured thereto, by means of which they may be removed when it is desired to remove or store the heater portions. The separable stove body permits the use of a stove of adequate dimensions, yet enables the storing or housing of the same when not in use in space beneath the seats of the car or vehicle, which space has no other use.

It will thus be seen that there is provided apparatus of compact construction by means of which the objects of this invention are attained. The parts are simple and inexpensive and may be quickly and readily assembled or disassembled. While there is shown a heater adapted to use coal, it will, of course, be understood that a liquid fuel burning heater might be constructed in such manner as to embody certain features of the invention.

It will be noted upon reference to Figs. 1 and 3 that the openings 5 which receive the fastening screws for securing the base to the floor of the car, are arranged within the diameter of the stove, the lower part of the base being somewhat contracted to permit this to be done. While not essential, this is advantageous in that it avoids any projection which might trip occupants of the vehicle or be in the way.

In Fig. 6 the smoke-pipe sections are shown with stops to limit the relative movement of said sections, a precaution which is advisable where more than two sections of pipe are employed, to guard against the possible separation of the sections through jarring or vibration. The plate or collar 25 secured to the upper section of the pipe limits the projection of said section into the hood or above the car roof, yet insures its

projecting sufficiently above the roof. Without this, and where as will usually be the case, a hood is employed, the upper end of the pipe might be so far projected into the hood as materially to interfere with the draft.

These minor details hence contribute to the proper adjustment and maintenance of relation between parts, and insure satisfactory operation.

It is obvious that many modifications are possible in the details of the structure above described and we do not confine ourselves to the particular embodiments above described.

Having described our invention, what we claim as new and desire to secure by Letters Patent is:

1. In combination with a car having a smoke-pipe opening and a hood therefor, a plate or collar secured about said opening; a heater separable between its upper and lower extremities into two sections; means for quickly and securely uniting the sections of the heater one to the other; means for quickly securing the base section of the heater to the car floor; a telescopic smoke-pipe; means for readily securing the lower section of the smoke-pipe to the heater; and means for readily securing the upper section of the smoke-pipe to the collar and positioning its upper extremity with reference to the car roof and to the pipe opening therein.

2. In combination with a vehicle having a smoke-pipe opening, an emergency heating equipment comprising an upright stove consisting of an upper or body section and a lower or base section of measurement permitting storage of said sections beneath seats of a car; interlocking devices carried by said sections, whereby they may be readily and securely locked together or disconnected at will; means located substantially within the diameter of the base section for readily securing said base to the car floor; a telescopic smoke-pipe provided with stops to prevent separation of its sections when extended; and means for positioning the upper section of said pipe relatively to the smoke-pipe opening, and for firmly securing the same in such adjusted position, the separable construction permitting the stove sections to be disassociated for storage beneath the seats of the car and the telescopic smoke-pipe permitting the pipe to be contracted and placed within a section of the stove.

3. An emergency heating equipment for vehicles comprising, in combination, an upright stove of a cross section admitting of the storage of its sections beneath seats of the vehicle; interlocking devices carried by said stove sections, and serving reliably to secure one to the other and prevent accidental separation; a telescopic smoke-pipe; means for reliably securing the lower section of the pipe to the stove; means carried by

the upper section of said pipe for reliably securing the same to the roof of the vehicle and positioning the same with reference to the pipe opening therein so that the pipe 5 shall not project unduly outside the vehicle; and means carried by the base section of the stove whereby it may be readily secured to the floor of a vehicle, the construction being such that the parts may be connected and 10 secured or disconnected and released, read-

ily and without the aid of special tools or appliances.

In testimony whereof we affix our signatures, in the presence of two witnesses.

WILLIAM R. McKEEN, JR.
BARTHOLOMEW JULIEN.
